DIRECT AND MESNE ASSIGNMENTS, TO SAMUEL LOEWY, OF NEW YORK, N. Y.

MACHINE FOR PACKAGING POWDERS.

1,091,568.

Specification of Letters Patent. Patented Mar. 31, 1914.

Application filed March 13, 1912. Serial No. 683,479.

To all whom it may concern:

Be it known that we, ISIDOR Z. GARFIELD, a citizen of the United States of America, residing in New York, borough of Manhattan, county and State of New York, and NATHAN GOLDFARB, a citizen of the United States of America, residing in New York, borough of Brooklyn, county of Kings, and State of New York, have invented certain new and useful Improvements in Machines for Packaging Powders, of which the following is a specification.

This invention relates to an improved machine for packaging powders, such as Seidlitz powders, Rochelle salts and similar powders for medicinal use, by which the powder is fed in accurately-measured quantities and in a temporarily compressed state to an intermittently-moving paper-band from which wrapper-blanks of the required size are cut, closed by a double-fold at the sides and ends and then successively fed after the closed packages are subjected to pressure for crushing the cakes in the same to a delivery and counting mechanism whereby the manual work heretofore required for packaging such powders is dispensed with, and the same quickly and effectively packaged without loss of powder; and for this purpose the invention consists of an organized machine for packaging powders, which comprises means for measuring uniform quantities of the powder, compressing them into cakes and delivering them to a continuous intermittently-movable paper-band below said compressing means, a folding mechanism for folding the sides of the wrappers into a double-fold over the cakes, means for cutting off the wrapper-blanks from the continuous paper-band, and means for folding the ends of each wrapper on the body-portions of the same, and means for delivering and counting said packages.

The invention consists further of certain details of construction of the different cooperating parts of the machine, which will be first fully described and finally pointed out in the claims.

In the accompanying drawings, Figure 1 represents a plan-view of the left-hand portion of our improved machine for packaging powders, Fig. 2 is a vertical longitudinal section on line 4—4, Fig. 1, Fig. 3 is a plan-view of the right-hand portion of the

machine, Figs. 4, 4^a, 4^b and 4^c are vertical transverse sections showing the successive steps of side-folding the wrapping-paper over the cakes of powder fed to the continuous, intermittently-moving band, Figs. 60 5 and 6 show respectively, a side-elevation and a vertical transverse section, on line 6—6, Fig. 3, of the powder-measuring, compressing and delivering mechanism, Fig. 7 is a detail side-elevation of the lower portion of the feed-hopper showing the means for regulating the supply of powder to the compressing mechanism, Fig. 8 is a side-elevation of the left-hand end of the machine, showing the mechanism for intermittently-feeding the paper-band, the cutting off mechanism, and the mechanism for folding and closing the ends of the wrappers, Fig. 9 represents a vertical transverse section with the mechanism for folding the 75 ends of the wrappers over the body-portions of the same, and Figs. 10^a, 10^b and 10^c represent respectively perspective views and an end-view of the wrappers in the different stages of folding over and closing 80 the ends of the same.

Similar letters of reference indicate corresponding parts throughout the several figures of the drawings.

Our organized machine for packaging 85 medicinal powders by mechanical means into paper-wrappers consists of a machine for measuring the powders in uniform quantities and temporarily compressing them 90 into cakes, and feeding them to a continuous paper-band which is intermittently moved forward below the measuring and compressing mechanism, a primary folder for creasing one side of the paper-band, a plurality of folders for doubling up and folding the 95 sides of the paper-band, and intermittently-actuated cutting mechanism for cutting off the side-folded paper-band into individual wrappers, means for folding over and closing 100 the ends of the wrappers, and means for delivering the packaged powders successively into a slideable tray for removing the same from the machine, and a counter for counting the number of packages delivered by the machine.

The powder-measuring and compressing machine.—This mechanism consists of a feed-hopper H into which the powder to be packaged is placed. The powder may be any suitable medicinal powder, but preferably

either sodium bi-carbonate or pulverized tartaric acid when the packages are made for Seidlitz powders which are usually wrapped into conventional blue and white paper. In the hopper H is arranged about midway of its height a rotary agitator h, the arms of which keep the powder in motion, break up any lumps and prevent the clogging of the same. The stirrer-shaft h¹ receives an intermittent rotary motion by suitable power-transmitting mechanism from the driving-shaft S of the machine. At the lower end of the hopper H is arranged a box-shaped delivery-portion H¹ in which is arranged a second transverse shaft h² which is preferably made of square shape at the inside of the box-shaped portion H¹ and which is provided on each of its sides with brushes h³. The brush-shaft h² receives like the stirrer-shaft h¹ intermittent rotary motion so that the brushes are moved over a horizontal screen h⁴ which is supported on suitable cleats h⁵ at the bottom of the box-shaped portion H¹ so as to feed a uniform quantity of powder into the space below the screen and deliver it through a central opening o, of round, square or oblong shape, in the bottom of the box-shaped portion H¹ into corresponding openings o¹ arranged in the circumference of a cylindrical drum D which is located below the hopper and to which intermittent rotary motion is imparted from the driving-shaft S. By the motion of the drum D, one opening o¹ after the other is brought into register with the delivery opening o in the bottom of the box-shaped portion H¹. In the drawing, the drum D is arranged with six openings, but it is obvious that any other number of openings may be arranged in the same. The drum D is provided at each inlet-opening o¹ with a stationary compressing cylinder d in which is located a piston d¹ having a piston-rod d² which is guided in an opening of the closed inner end of the cylinder d. Intermittent motion is imparted to the pistons d¹ so as to produce first the compression of the measured off quantity of powder, next a forward motion for delivering the compressed cakes onto a paper-wrapper, and then a return-motion for returning the pistons into their initial position for receiving the next quantity of powder through the feed-opening o in the lower box-shaped portion of the hopper. The shape of the cylinder and pistons corresponds to the shape of the feed-openings o and o¹. Each compressing cylinder d is provided sidewise of the piston-rod d² with a stop-screw d³ by which the inward adjustment of the piston is regulated and the same held in a fixed position when receiving the powder delivered to the cylinder. The positions of the stop-screws d³ are adjusted according to the quantity of powder which is to be delivered to the piston

and the degree of compression to be imparted to the cakes. The quantity of powder to be delivered to each compressing cylinder of the drum D is furthermore regulated by raising the brush-shaft h² into a somewhat higher or lower position in the box-shaped portion H¹ by means of two exterior plates h⁶ located at opposite sides of the box-shaped portion H¹, which plates are pivoted at one end of the side-wall of the box H¹ and provided with bearings for the ends of the shaft h². The shaft h² is guided in slots o² of the side-walls of the box-shaped portion H¹. The opposite end of each pivot-plate h⁶ is provided with an arc-shaped recess h⁷ through which is passed a clamping-screw h⁸, as shown in Fig. 7, for permitting the vertical adjustment of the plates h⁶ and shaft h² and thereby the more effective feed-action of the brushes h³ on the powder in the box-shaped portion H¹ and the delivery of a smaller or larger quantity of powder through the feed-openings o into the cylinder d then below the opening o. The adjusting plates are arranged at opposite sides of the box-shaped portion H¹ so as to set thereby the shaft of the feed-brushes at both ends slightly higher or lower relatively to the screen h⁴. The feed-brushes h³ force the powder with a variable pressure through the meshes of the screen h⁴ and feed after proper adjustment a uniform quantity of powder through the same. The exact quantity required is fed to each compressing-cylinder of the drum D after the feed-brushes on the one hand and the pistons on the other hand are properly adjusted, so that these measuring devices operate with an accuracy equal to weighing devices. For some powders, especially for pulverized crystalline powder, such as tartaric acid, the screen can be dispensed with, as they are not liable to clog and move freely and easily under the pressure of the brushes to and through the feed-opening, while for impalpable powders, such as sodium bi-carbonate, it is preferable to use a screen and force the powder through the meshes of the same. Intermittent rotary motion is imparted to the drum D and simultaneously to the shaft of the agitator and feed-brushes from the driving-shaft S by means of a pinion p on the same, which pinion meshes with a gear-wheel p' that is mounted on a short intermediate shaft S' said shaft being supported in journal-bearings of the supporting-frame. A wrist-pin p² on the gear-wheel p' is connected by a pivot-rod p³ with a crank-arm p⁴ on a shaft S³ which is likewise supported in journal-bearings of the supporting-frame of the machine. On the shaft S³ is mounted a ratchet-wheel p⁵ which is provided with as many teeth and recesses as there are compressing-cylinders in the drum, the recesses of the ratchet-wheel being engaged by a

spring-actuated pawl p^6 on the outer end of the crank-arm p^4 and by a check-pawl p^7 . A second crank-arm p^8 is mounted on the shaft S^3 and connected by a pivot-rod p^9 with a crank-arm p^{10} and by a pawl p^{11} at the end of the pivot-rod p^9 with a ratchet-wheel p^{12} keyed to the shaft S^4 of the drum D, so that by the intermediate pawl and ratchet-wheel mechanisms and crank connections, an intermittent rotary motion equal to 1/6th of the circumference of the drum is imparted to the same and thereby one compressing-cylinder after the other fed into register with the feed-opening in the bottom of the box-shaped hopper-portion H^1 . On the intermediate shaft S^3 is mounted sidewise of the ratchet-wheel p^6 a gear-wheel p^{15} which meshes with a pinion p^{14} on the short shaft p^{12} which is supported in bearings of the machine-frame. On the shaft p^{12} is keyed a sprocket-wheel p^{16} which transmits by a sprocket-chain p^{17} and wheel p^{18} intermittent rotary motion to the shaft h^2 of the feed-brushes and by another sprocket-wheel and chain transmission p^{19} and p^{20} to the shaft h^1 of the agitator h , as shown in Fig. 5. On the supporting-frame for the motion-transmitting mechanism is supported an inclined block B, the concave face of which is concentric with the drum D and forms contact with the circumference face of the drum, as shown in Figs. 5 and 6, and closes thereby throughout the rotation of the drum the opening o^1 of the same which is at the time in register with the face of the block B. This block B serves to hold the charge of powder supplied to the openings o^1 of the drum and to the cylinders d , while the inner ends of the pistons receive an outward motion by an intermediate mechanism, which is shown clearly in Fig. 5 and which consists of an oscillating lever b , which is fulcrumed to a fixed supporting arm b' on the frame of the machine. The upper end of the arm b acts on the piston-rods of the cylinders while its outer slotted end is actuated by a connecting-rod b^2 , the upper end of which is pivoted to a wrist-pin b^3 on a crank-disk b^4 placed on the shaft p^{12} of the sprocket wheel p^{16} . By adjusting the lower end of the connecting-rod b^2 nearer to or farther away from the fulcrum of the oscillating bar b , the compression of the powder in the compressing cylinders of the drum D is regulated in proportion to the greater or smaller degree of compactness to which it is to be compressed. This compression takes place when the drum D has completed one-sixth part of its rotation which commences with the registering of the first cylinder with the feed-opening of the hopper. When the drum is moved for the next one-sixth of its rotation, the compressed cake of powder is held without any further action in its cylinder while at the end of the third one-

sixth part of the rotation of the cylinder the cake arrives at a point diametrically opposite to the feed-opening o and is delivered onto a wrapper placed below the drum on the base-plate of the machine, by the action of a curved pusher e , which forms the upper arm of an elbow-lever e' that is pivoted to a standard e^2 attached to the base-plate of the machine. The elbow-lever e' is connected at its apex by a pivot-rod e^3 with the wrist-pin b^3 on the crank-disk b^4 so as to be operated at the proper time whenever one of the compressing cylinders arrives at the end of the third one-sixth part of the rotation of the drum. The pusher e acts on the piston-rod d^2 and pushes the piston d^1 downward and delivers the cake from the cylinders to the wrapper. During the next one-sixth part of the rotation of the drum D, the piston remains in its forward position in the cylinder, as shown in Fig. 6, while after the fifth one-sixth part of the rotation of the drum D, the piston d^1 is returned into its normal position at the inside of the cylinder into contact with its stop-screw d^3 by a pusher-lever f which is fulcrumed to an upright standard f' on the base of the supporting-frame, said pusher-lever being provided with an arm f^2 that extends inwardly into the cylinder so as to contact with the piston of the same and return the piston into its initial position ready to receive the next charge when the drum arrives at the end of the last one-sixth part of its rotation in register with the feed-opening of the box-shaped portion H^1 . The lower end of the fulcrumed pusher-lever f is connected by a pivot-rod f^3 with the wrist-pin b^3 on the crank-disk b^4 so that the pusher-lever is actuated at each full rotation of the crank-disk. During the next rotation of the drum the same steps, namely, feeding the powder, compressing it into a cake, delivering it onto a wrapper, and returning the piston, are successively repeated for each rotation of the drum and as many cakes of powder delivered as there are compressing cylinders in the drum. As some of the powder is carried along from the feed-opening o on the exterior surface of the drum D, as each cylinder passes beyond the feed-opening of the box-shaped portion H^1 , a scraper g is arranged in contact with the surface of the cylinder D, the upper end of the scraper being attached to the end-wall of the box-shaped portion H^1 . By means of the scraper, any adhering powder is removed from the surface of the drum and delivered over the side-edges of the drum to a suitable receptacle without being conducted into the narrow space between the compressing cylinders d and the compressing block B so that not the slightest increase in the quantity of powder in the compression-space between the cylinder and

block can take place. At one side of the hopper H is arranged a spring-actuated knocker h², the spring-arm of which is actuated by the sprocket-wheel on the shaft 5 h². The blows of the knocker on the lower part of the hopper shake up the powder and deliver it freely to the feed-brushes.

The measuring and compressing machine forms the subject-matter of a separate application filed by Isidor Z. Garfield on March 10 13, 1912, Ser. No. 683,522.

It is obvious that any other measuring and compressing mechanism for delivering cakes of uniform weight and round or other 15 shape may be employed.

The feeding and side-folding mechanism of the paper band.—The paper is supplied from a roll which is supported at the right-hand end of the supporting-frame of the 20 machine, and from which a suitable length is unwound by a suitable unwinding mechanism (not shown) so that it can be easily moved forward over its guide-plate F' through the folding device. The width of 25 the paper-band is equal to the width of the wrappers required for the packages. The temporarily-compressed cakes are dropped at the required equal distances from each other on the intermittently-movable paper-band so that a sufficient space is left between the cakes to bring them into the center of the wrapper-blanks. The intermittent feed of the paper-band is imparted from the shaft S' of the gear-wheel p' to 30 a shaft S⁵ which is connected by a universal joint j with the shaft S' and by another universal joint j' with a horizontal shaft S⁶ which turns in suitable bearings of a separate supporting-frame F for the 35 left-hand end of the machine and which supplies the required power for the intermittent feeding of the paper-band over the supporting guide-plate F' that extends from the compressing drum to the frame F, also 40 the power for actuating the cutting off, end-folding, delivering and counting mechanisms. The frame F' is connected with the frame of the compressing machine by longitudinal parallel bars F². On the right-hand 45 end of the shaft S⁶ is mounted a worm-wheel w which meshes with a second worm-wheel w' of equal size, which is located at right angles to the worm-wheel w below the same and the shaft w² of which is supported in bracket-bearings of the frame F for transmitting by a crank-rod w⁴ connected with a wrist-pin w³ on the worm-wheel w' oscillating motion to lever w⁵, which is pivoted at its lower end to a cross- 50 bar F³ of the frame F and which is pivotally connected at its upper end with a reciprocating carriage w⁶, guided on ways w⁷ of the frame F. In ears at the upper front-end of the reciprocating carriage w⁶ is supported a lateral pivot-shaft w⁸ which ex-

tends over the side-folded paper-band and which carries a downwardly projecting feed-pawl w⁹, that is pressed in downward direction during the forward motion of the carriage by a spring-finger w¹⁰ which presses on the upper curved edge of the feed-pawl, as shown in Figs. 1 and 8. The worm-wheel transmission is so proportioned that for each rotation of the gear-wheel p' and shaft S⁶, an oscillating forward and backward motion is imparted to the lever w⁵ so that it moves at each forward motion by the engagement of the sharp edge of the pawl w⁹ the paper-band forward immediately after a cake of powder has been delivered by the compressing drum on the same. The biting action of the pawl and the forward feeding of the paper-band takes place during the oscillating motion of the lever w⁵ toward the left, while by the return-motion of the lever w⁵ toward the right the feed-pawl is moved freely in backward direction over the paper-band ready for the next feed-motion of the pawl. A transverse bar w¹¹ on the reciprocating carriage w⁶ extends over the paper-band adjacent to the feed-pawl w⁹, as shown in Fig. 1, and holds thereby the paper-band in position for being fed by the feed-pawl over its supporting guide-plate F' toward the end-folding mechanism at the left-hand end of the machine.

By the forward movement of the paper-band over its supporting guide-plate F', there is first formed at one edge by an inclined folder i, and creaser i', which are arranged on the left-hand side of the guide-plate F' near the compressing drum, a narrow creased edge-strip l, as shown in Fig. 4. The folder i bends over the edge l and the creaser i' being smaller in size than the folder i, produces the crease-line in the paper-band. Simultaneously therewith the left-hand side of the paper-band is folded over the cakes toward the right-hand side of the same, as shown in Fig. 4^a. The creased edge-strip l serves to contact with the paper-band and serves to hold the folded-over portion in a slightly-curved position, in the nature of a loose bight so that pressure on the cakes is prevented and the same carried along with the paper-band until the paper-band is double-folded at its right-hand side. The double side-folding of the paper-band is accomplished gradually by the successive action of the turn-over folders, i², i³, i⁴, which are arranged on the right-hand side of the guide-plate F', as shown in Fig. 1. The folders i², i³, i⁴ fold the right-hand side of the paper-band over the creased strip, as shown at l' and then fold it with the creased strip into a double fold l², as shown in the Figs. 4^a, 4^b, and 4^c respectively, so that when the paper-band arrives near the feed-pawl it is closed 132

by the double fold. During the side folding of the paper-band, the folded portion is held on the guide-plate by suitable cross-strips. After the side-folded paper-band has passed 5 beyond the feed-pawl, it is cut off midway between the cakes delivered thereto by a fulcrumed cutting device C which consists of a stationary knife k and an oscillating and vertically reciprocating knife k', which latter is operated by means of a downwardly-extending cam k² on the shaft S⁶, said cam engaging a pin k³ at the lower end of a pivoted arm k⁴ which is held by a spring k⁵ in contact with the cam k² while the cutting operation takes place. The portion of the 10 side-folded paper-band, which has been moved past the cutting-device into the end-folding mechanism is thus cut off and forms the wrapper proper, which is then folded at 15 the ends and moved forward for delivery.

The end-folding mechanism.—The side-folded wrapper containing the cake is next taken up by the end-folding mechanism and moved through an angle of 90° from its horizontal position into a vertical position by 20 an oscillating plate or platform n of the end-closing mechanism. The platform n is hinged at its inner end and connected at the underside of its forward end with an actuating connecting-rod n', the lower end of which is connected by an anti-friction roller n² with the cam-groove of a cam n³ on the shaft S⁶. Each rotation of the shaft S⁶ imparts an up and down tilting motion to the 25 platform n and moves thereby the wrapper into vertical position along stationary side-walls n⁴ by which the wrapper-ends are bent over at right angles to the body-portion of the wrapper l³, as shown in dotted lines in Fig. 10^a and in full lines in Fig. 10^b. During 30 the upwardly-tilting motion of the wrapper, it is passed along by a spring-finger n⁵. In this position the rectangularly bent-over ends of the wrapper are acted upon by laterally-oscillating fingers n⁶ which fold the 35 bent-up ends of the wrapper over on the body-portion of the same, as shown in Fig. 10^c. The motion of the fingers n⁶ is accomplished by means of fulcrumed levers n⁷ 40 which are pivoted at their upper ends to the lower ends of the fingers n⁶ and at their lower slotted ends to a pin on the cam-rod n' of the platform, so that during the upward motion of the cam-rod n' the fingers 45 are moved outwardly and during the downward motion of the platform inwardly for folding the ends of the wrappers over the body-portion of the same. The end-folded 50 wrapper is next pushed forward by the next following end-folded wrapper over curved 55 guide-fingers n⁸ into the adjacent end r' of a delivery-channel r. The connecting-end r' of the delivery channel r is curved in the 60 form of a quadrant of a circle while the 65 main-portion is straight and arranged paral-

lel with and alongside of the supporting guide-plate for the paper-band, as shown in Fig. 1. A second spring-actuated finger n⁹ extends over the upper edge of the raised wrappers so as to hold them in proper position for being pushed forward into the curved portion of the delivery-channel r. The upper edges of the wrappers are then passed under a stationary angular guide-arm n¹⁰ and then forward between the curved 70 side-walls of the delivery-channel into the straight main-portion of the same.

Alongside of the curved end-portion r' of the delivery-channel r is arranged an intermittently-rotated disk n¹¹ which is provided 80 with pins n¹² on its face that are engaged by a spring-pawl n¹² which is operated by means of a spring-actuated connecting-rod n¹³ having an anti-friction roller n¹⁴ at its lower end. The roller n¹⁴ engages a cam 85 n¹⁵ at the outermost end of the shaft S⁶ so that the disk n¹¹ is turned for one twelfth part of its rotation on every rotation of the shaft S⁶. For this purpose the disk n¹¹ is provided with twelve teeth or pins on its 90 face. On the circumference of the disk n¹¹ is arranged in radial alinement with one of the pins, a longer tooth n¹⁶ which engages the downwardly-extending arm n¹⁷ of a 95 rocking-lever n¹⁸ and produces the lifting of the longer arm of the rocking-lever n¹⁸ that enters through a slot in the side-wall of the curved portion of the delivery-channel r and the raising of every twelfth wrapper 100 into a diagonally inclined position, as shown in Fig. 2, so as to separate thereby the wrappers into dozens for the convenient packing into boxes for shipment. The wrappers are pushed forward along the curved portion of the delivery-channel into the straight portion, while the inclined separating wrappers are guided along the upper edge of the outer side-wall of the delivery-channel r.

In place of dividing the wrappers into groups of one dozen each, they may be divided into groups of ten wrappers, in which case, however, the actuating disk for the rocking-lever is to be provided with ten instead of twelve teeth.

By the pressure exerted on the package 115 during the folding over of the ends of the wrappers and by the forcible forward pushing of the same into the delivery-channel a sufficient pressure is exerted on the body-portion of the wrappers for crushing the 120 cakes in the same and changing them back into powder-form so that flat wrappers of the usual shape are obtained.

The delivery mechanism.—The delivery mechanism consists of the delivery-channel r, a plate r² which is located in and guided by the side-walls of the channel r, and a delivery-tray r³ which is placed in the channel and pushed under the plate r². To the delivery-plate r² a horizontally-reciprocating 130

ing motion is imparted by means of a transverse rod r^4 which is attached to the upper slotted end of the oscillating lever w^5 and which serves to engage one or the other of two downwardly-extending pins r^5 on the ingoing end of the delivery-plate r^2 , as shown in Figs. 1 and 2. The pins r^5 pass through slots r^6 in the bottom of the delivery-channel r . The delivery-plate r^2 is provided at opposite sides with flat crimped-up inclined teeth r^7 which during the left-hand motion of the delivery-plate are moved under the lower edges of the wrappers fed to the same from the curved portion r' of the delivery-channel and then carried along by the motion of the delivery-plate r^2 toward the right over toward and on a delivery-tray r^3 until the same is entirely filled up with wrappers divided into groups of twelve by every inclined twelfth package. The flat teeth of the delivery-plate r^2 gradually push the wrappers forward so that the same do not exert any backward pressure on the wrappers in the curved portion r' and the end-folding mechanism. When the delivery-tray r^3 is gradually filled up with wrappers, it is removed and a new tray placed in position under the reciprocating delivery-plate to be filled again with wrappers delivered by the delivery-plate. Simultaneously with the oscillating motion of the lever w^5 , a counter D' is operated by an oscillating connecting-rod u which is pivoted to the reciprocation rod r^4 at one end and connected with a crank u' on the counter-shaft at its opposite slotted end by a pin u^2 so that the shaft of the counter is operated whenever the connecting-rod u arrives at the end of its motion. The counter serves for counting the total number of wrappers made and delivered by the machine within a given time.

The machine is mainly intended for packaging Seidlitz-powders, but it is obvious that any other powders which are to be packed into wrappers closed at the sides and ends, can be packed by the same, without loss or waste, which is mainly due to the temporary compression of the powder into cakes, which cakes are afterward, by the end-folding of the wrappers and the pressure exerted thereon, crushed and changed into powder-form, the temporary compression of the powder into cakes serving only for the purpose of preventing loss of material and from the wrappers during the folding operations and during the transmission of the wrappers from the measuring and compressing mechanisms to the end-folding and delivering mechanisms.

We claim:

1. An organized machine for packaging powders, which comprises a combined measuring and compressing device for temporarily compressing the powder into cakes,

means for delivering the cakes formed by said device, means for intermittently moving a paper-band below said delivering means, side-folding mechanisms for side-folding and closing said paper-band over said cakes, an intermittently-actuated cutting knife for cutting off the paper-band successively into individual wrappers, an end-folding mechanism for the wrappers, and an intermittently-reciprocating delivery-mechanism for the closed packages. 70 75

2. An organized machine for packaging medicinal and other powders, which comprises means for measuring the powder into definite quantities, means for temporarily compressing the same into cakes, means for delivering the cakes onto a paper-band, means for intermittently moving said paper-band past the compressing and delivering means, means for side-creasing and double-folding the paper-band over the cakes, an intermittently-actuated cutting-off device for the paper-band, an end-folding mechanism for the wrappers cut off from the paper-band, and an intermittently-actuated and horizontally-reciprocating delivery-mechanism for the closed packages. 80 85

3. In a machine for packaging powders, the combination, with a combined measuring and compressing device for the powder, 95 of means for delivering the cakes formed by the said measuring and compressing device to a paper-band, means for intermittently feeding said paper-band past the delivery means, means for side-creasing and 100 double-folding the paper-band over the cakes delivered to the paper-band, and an intermittently-actuated cutting knife for cutting the side-folded paper-band into individual wrappers. 105

4. In a machine for packaging powders, the combination of an end-folding mechanism for the wrappers, comprising a tilting-platform, stationary side-walls for bending over the ends of the wrappers, and laterally-oscillating folders for closing the ends of the wrappers onto the body of the package, a delivery-channel, means for guiding the packages onto said delivery-channel, and means for lifting one of the packages into 110 inclined position after a certain predetermined quantity has been supplied to the ingoing end of the delivery mechanism.

5. In a machine for packaging powders, the combination of an end-folding mechanism for the wrappers, comprising a tilting-platform, stationary side-walls for bending over the ends of the wrappers, and laterally-oscillating folders for closing the ends of the wrappers onto the body of the package, a delivery-channel, a horizontally-reciprocating delivery-plate provided with flat inclined side-teeth, and a removable delivery-tray communicating with the outgoing end of the delivery-plate. 120 125 130

6. In a machine for packaging powders, the combination, with an end-folding mechanism for side-folded wrappers, comprising stationary side-walls, a tilting platform between the same, spring-actuated fingers for holding the wrappers in position while being tilted, and laterally-oscillating folders for closing the ends of the wrappers, of a delivery-channel, and an intermittently-reciprocating delivery mechanism for the closed packages.

7. In a machine for packaging powders, the combination, with an end-folding mechanism for the side-folded wrappers, comprising stationary side-walls, an intermittently-tilting platform between the same, spring-actuated fingers for holding the wrappers in position while being tilted, and

laterally-reciprocating folders, of a delivery-channel adjacent to the end-folding mechanism, an intermittently actuated lifting device for moving a closed package into inclined position after a predetermined number has been delivered, an intermittently-reciprocating delivery-plate having flat pusher-teeth, and a delivery-tray for receiving the packages from the pusher-plate.

In testimony, that we claim the foregoing as our invention, we have signed our names in presence of two subscribing witnesses.

ISIDOR Z. GARFIELD.
NATHAN GOLDFARB.
